UNITED STATES PATENT OFFICE.

ONESIME E. MICHAUD, OF ST. LOUIS, MISSOURI.

INTERNAL-COMBUSTION MOTOR.

1,132,278.

Specification of Letters Patent. Patented Mar. 16, 1915.

Application filed June 23, 1913. Serial No. 706,898.

To all whom it may concern:

Be it known that I, ONESIME E. MICHAUD, a citizen of the United States, and a resident of the city of St. Louis and State of Missouri, have invented a new and useful Improvement in Internal-Combustion Motors, of which the following is a specification.

This invention relates to internal combustion motors, and more particularly to those of the four stroke or four cycle type.

10 It has for its principal objects to improve upon the inlet and exhaust valves of such motors and the manner of operating the same, and to attain certain advantages which will hereinafter more fully appear.

15 The invention consists in the parts and in the arrangements and combinations of parts hereinafter described and claimed.

20 In the accompanying drawings, which form part of this specification and wherein like symbols refer to like parts wherever they occur, —Figure 1 is an elevation of the exhaust side of a four cylinder internal combustion motor embodying the invention; Fig. 2 is a fragmentary view partly in vertical section and partly in elevation of the 25 intake side of the motor; Fig. 3 is a top plan; Fig. 4 is a vertical section on the line 4—4 of Fig. 1; Fig. 5 is an end elevation; Fig. 6 is a view showing the intake and exhaust valves detached; and Figs. 7, 30 8, 9 and 10 are schematic views showing the relative positions of the inlet and exhaust valves at the beginning of each stroke 35 of the piston and also the relative order of the strokes of the pistons of the four cylinders.

The motor illustrated in the drawings has four cylinders 1, 2, 3 and 4, respectively. 40 The cylinders are mounted on the crank case 5 which is divided horizontally in accordance with the usual practice and has journaled therein a crank shaft 6 which is of the ordinary four throw type and is connected to the respective pistons 7 by rods 8.

The cylinders have annular water spaces 9 extending around their upper portions. The cylinder heads also have spaces 10 communicating with said annular spaces 9. The water is circulated by a pump 11 which may be connected to a radiator (not shown) through a pipe 12. The pump is connected through a pipe 13 to a manifold 14 having branches 15 communicating with the water spaces 9 of the respective cylinders. The

water spaces 10 in the cylinder heads are respectively connected to a manifold 16 through branches 17. This manifold 16 may also be connected to the radiator. The 60 pump may be driven from the crank shaft through the medium of any suitable gearing, but preferably by a sprocket chain 18 passing around the sprocket wheels 19 and 20 fixed respectively on the pump shaft and 65 crank shaft.

The cylinders are each provided on opposite sides with intake and exhaust ports 21 and 22 respectively. Each of the ports opens into a horizontal semi-circular recess 70 provided in a boss or lateral extension 23 of the cylinder and constituting a seat for a cylindrical rotary valve. The intake valve is indicated by the numeral 24 and the exhaust valve by the numeral 25. The respective valves are tubular and substantially alike in construction, the difference being in the location of their ports which are relatively arranged according to the timing of the power stroke of the respective cylinders 75 so as will presently appear.

The valve members 24 and 25 as shown are each made in two sections for convenience in grinding and fitting. The respective tubular sections are closed at both ends 85 and span two cylinders. They have ports which are adapted to respectively register with the intake and exhaust ports of the cylinders. The ports of the intake valve are numbered 24¹, 24², 24³ and 24⁴ for the cylinders 1, 2, 3 and 4, respectively; while the ports of the exhaust valve are numbered 25¹, 25², 25³ and 25⁴.

The valve members are provided with annular ribs 26 on opposite sides of the 95 ports which rotate in grooves provided at opposite ends of the bosses or extensions 23. Cap pieces 27 are provided to secure the valve members in place. These cap pieces have semi-cylindrical portions in which the 100 valve members rotate and they are also provided at their ends with grooves for the reception of the ribs 26. As shown in Figs. 3 and 4 the lower end portions of these cap pieces are bolted to the vertical faces 105 of the bosses 23 and their upper ends are extended angularly and bolted to the top of the cylinder head; and by placing shims 27^a of different thicknesses under the cap pieces the wear can be taken up so that 110 there will be no leakage.

The valve sections 24 and 25 have middle

openings 28 which are adapted to communicate with supply and exhaust manifolds 29 and 30 respectively. These manifolds have upturned end portions to which are attached bearing members 31 having openings 32 so as to communicate with the openings 28 in said valve members. Cap pieces 33 are secured to the bearing pieces 31 and said bearing members and cap pieces are provided with grooves at their ends adapted to receive the annular ribs 26 which are provided on opposite sides of the openings 28. These ribs 26 and those above mentioned which coöperate with the bosses 23 and cap pieces 27 serve as end thrust bearings for the valve members and also enable a tight joint being made without a great amount of friction.

The companion valve members may be fastened so as to rotate together in any suitable manner, but it is preferable to provide a square groove in the end of one member in which is fitted a round rib or bead on the other member so as to permit an oscillatory movement of one member with respect to the other and yet compel them to rotate in unison. The valve members are provided with extensions 34 on which are secured spur gears 35 meshing with an intermediate gear 36 mounted on a stub shaft 37. On this stub shaft is fixed a sprocket wheel 38 which is driven by a sprocket chain 39 running over a sprocket wheel 40 on the crank shaft of the motor. By this arrangement the intake and exhaust valves are rotated simultaneously and at the same speed which is at the ratio of two to one with respect to the crank shaft. That is, the crank shaft makes two revolutions for each revolution of the valves. Or in other words, the valves make one revolution during the four cycles of the pistons.

As above mentioned, the motor is of the four cycle type. Consequently the ports 24^a and 25^a respectively of the intake and exhaust valves must be brought into register with the intake and exhaust ports of the cylinder once in a complete cycle. The cylinders are preferably fired in the order of 1, 3, 4, 2. That is, the power strokes of the pistons of the cylinders follow in succession in the order named. In Fig. 10 (cylinder No. 1) the piston is shown up ready for the power stroke. Fig. 8 (cylinder No. 3) the piston is down ready for the compression stroke as it is the next cylinder to fire. Fig. 7 (cylinder No. 4) shows the piston up and intake valve port ready to move into register with the intake port in the cylinder so that the gas will be drawn into the cylinder as the piston descends. In Fig. 9 (cylinder No. 2) the piston is shown down ready for the exhaust stroke. This last mentioned cylinder has fired just prior to the cylinder No. 1.

The relative arrangement of the ports in the intake and exhaust valves will be varied according to the timing of the cylinders. In any case, however, the respective ports are arranged at an angle of 90 degrees or 70 on the quarter turn in advance of each other.

In order to lubricate the bearings for the valve members annular grooves 41 are provided in the respective bearings 23 and 31 and cap pieces 27 and 33. Supply pipes 42 leading from a manifold pipe 43 communicate with these grooves at convenient places so that oil is constantly supplied for the lubrication of the bearing without interfering with the combustible gases taken into the engine. The manifold may be connected with a gravity supply tank (not shown) in any obvious manner.

Obviously, the motor admits of considerable modification without departing from the invention. Therefore, I do not wish to be limited to the specific constructions and arrangements shown.

What I claim is:

1. In an internal combustion motor, the combination with a plurality of working cylinders arranged in a row and having inlet and exhaust ports on opposite sides, said cylinders having lateral projections 95 provided with horizontal semi-cylindrical valve seats into which the said ports respectively open, rotatory tubular valve members each arranged to coöperate with two adjoining cylinders and fitted in said seats and 100 having ports corresponding to the ports in the cylinders, said valve members having annular circumferential ribs on opposite sides of the ports therein, separate cap pieces fitted over said tubular valve members 105 and coöperating with the respective lateral projections of the cylinder to provide continuous bearings for said valve members, said lateral projections and cap pieces having coöperating semi-circular grooves providing continuous bearings for said annular ribs on the valve members, said tubular valve members being closed at both ends and having ports at the middle, and a manifold pipe having branches provided at their ends 110 with sleeves which are fitted on said valve members in the region of said middle ports.

2. In an internal combustion motor, the combination with a battery of working cylinders arranged in a row, said cylinders 120 having alined intake ports on one side and exhaust ports on the opposite side, said cylinders also having semi-cylindrical valve seats in the region of the respective ports, detachable cap pieces having counterpart 125 valve seats coöoperating with said semi-cylindrical valve seats, cylindrical tubular valve members fitted rotatably in said valve seats, said tubular valve members having closed ends and each being of sufficient 130

length and having ports arranged to co-operate with the respective ports of two adjoining working cylinders, said valve members having ports intermediate their ends, and supply and exhaust manifolds having extensions provided with terminal sleeves fitted rotatably on the respective valve members in the region of the intermediate ports therein and arranged and adapted to estab-

lish communication between the valve members and the respective manifolds.

Signed at Waco, Texas, this 24 day of June, 1912.

ONESIME E. MICHAUD.
